HEAT EXCHANGE APPARATUS

Edmund R. Walker, Kenmore, N. Y., assignor to
 Fedders Manufacturing Company, Inc., Buffalo,
 N. Y.

Application June 28, 1940, Serial No. 342,892

3 Claims. (Cl. 257—136)

This invention relates to heat exchange apparatus, and particularly to heater units which are useful in air conditioning systems.

The invention is directed to a novel structural organization of a heating coil unit and casing for housing such unit, wherein the casing is devised to support the coil unit in such manner that the coil may freely expand or contract in its normal plane, and yet be fully protected against all other physically or thermally activated strains. The residual stresses, which may be caused by differential expansion or contraction within the heating surfaces of the coil unit, are automatically absorbed by the structure of the tube components thereof, which are devised to yield individually by bending to accommodate themselves to the position of the remainder of their companion tubes without the application of direct thrust or tension loads on any portion of the structure.

Other features of the invention, including a novel steam distribution system, are more specifically set forth in the accompanying specification and drawings, wherein:

Fig. 1 is a front view of the coil unit;

Fig. 2 is an enlarged section on the line 2—2 of Fig. 1, with the lower portion shown in elevation;

Fig. 3 is an enlarged fragmentary section on the line 3—3 of Fig. 2;

Fig. 4 is a perspective view showing the orifice structure of the upper extremity of the tubes; and

Fig. 5 is a diagrammatic view showing several of the units applied to a portion of an air heating system.

The invention consists of a rigid fabricated casing 10 which serves to support and contain a coil unit 11. The casing 10 is formed of sheet metal parts, including top and bottom sections 14 and 15, and sides 16. The sides 16 are formed with marginal flanges 17 and 18, the latter or horizontal flanges supporting the sections 14 and 15 which are secured thereto by rivets 21 (Fig. 3). It will be seen in Fig. 2 that the sections 14 and 15 are provided with flanges 14a and 15a, and with offset central portions 14b and 15b, respectively, which latter portions serve to partially enclose the headers of the coil unit 11, as will be explained hereinafter.

The flanges 14a, 15a, and 17, it will be noted, all lie in a common plane, and thus they provide a continuous marginal pad P on each face of the casing, to which other casings may be secured, or to which a duct 28 and a blower

casing 21 may be attached, as shown diagrammatically in Fig. 5. Holes 22 are provided in the pads P at spaced intervals to receive bolts or rivets for securing the casing to such other units.

It will also be observed that at the corners of the pads P the extremities of the flanges 14a, 15a are slightly offset, as indicated by the numerals 24, to receive ears 25 on the flanges 17. Rivets 26 secure the parts together at these points.

On the sides of the casing, the exposed ends of the top and bottom sections 14 and 15 are covered by angle members 28, which members are secured to the horizontal flanges 18 of the sides 16 by rivets 29.

The coil unit 11 consists of upper and lower cylindrical headers 35 and 36, and connecting finned tubes 37. The headers are closed at each extremity by heads 38, which are soldered in place. Each head 38 is formed with a projecting mounting pintle 40. The extremities of the tubes 37 are entered in internally flanged holes 41 and 42 in the headers 35 and 36 respectively, and it will be seen in Fig. 4 that the extremities of the tubes, which lie within the header 35, are formed with rounded and reduced terminals 43 formed with angularly spaced ports 45 partially defined by intermediate and opposing jaws 46.

The tubes 37 are bent near their central portion, as indicated by the numeral 47, so that individual tubes may respond to expansion or contraction by arching between the supports provided by the headers 35 and 36.

The upper or steam header 35, at its center portion, carries brackets 48 which are rigidly connected to the top section 14 of the casing by rivets 49 (Figs. 2 and 3). The upper portion of this header lies within the offset portion 14b of the top section 14, and it is provided with an inlet nipple 50 which projects vertically through a clearance hole 51 in the offset portion 14b. The pintles 40 of the upper header 35 project through clearance holes 53 in the sides 16, and they enter bearings 54 of externally located brackets 55, which brackets are rigidly secured to the sides 16 by rivets 56 and 57.

A distributor plate 58 is secured within the header 35 immediately beneath the steam inlet nipple 50, and it is formed with two curved opposing surfaces 60a, 60b, which divide the entrant steam volume and direct it toward the extremities of the header 35.

The pintles 40 of the lower or return header 36 extend through slots 58 in the sides 16, and

they are received in brackets 60. The brackets 60 are similar to the brackets 55, except that they are formed with vertical slots 61 for receiving the ends of the pintles 40 of the lower header 36. The lower header 36 carries an integral outlet nipple 62, which projects through an opening 63 in the bottom section 15.

Bent plates 64 and 65 are secured to the upper and lower sections 14 and 15, where they serve as shrouds to direct the air in a smooth flow through the finned tube portion of the coil unit.

In a heating installation, it will first be observed that the central supports 48 of the upper header 35 transmit the load of the header and overlying steam supply piping S to the casing 10, so the coil is free of extraneous loads. Inasmuch as the upper header 35 is rigidly connected to the casing only by the centrally located supports 48, all other portions of the header are free to expand or contract without restraining influences. Such movements of this header are, however, limited only to longitudinal expansion or contraction, since the mounting of the header pintles 40 in the bearings 54 permits only axial movement of the ends of the headers, and warping or twisting effects are thus prevented.

It will be apparent that since the upper header 35 is fixed axially, expansion of the tubes 37 will cause free downward movement of the lower header 36 under the sole guidance of the pintles 40 thereof in the vertical slots 61 of the brackets 60. Thus, the lower header 36 is free at all times to accommodate itself to the dimensional changes of the tubes 37, as may be occasioned by thermal conditions within the coil unit.

In view of the fact that under unusual operating conditions differential expansion or contraction may occur between the various tubes 37, provision is made in the knee or bent portion 47 of each tube, so that each tube is in effect an eccentric column which may bend or warp between the headers. Thus, the lower header may, as previously noted, move in response to the expansive demands of a majority of the tubes, and at the same time the remainder of the tubes, even though expanding at a different rate or degree, will accommodate themselves automatically to the general movement without placing disruptive strains on their connection joints with the headers.

It will now be apparent that the structure of the casing is such that it serves as a rigid housing within which the coil unit is supported, so that it is free to expand in its normal or natural plane without restraint, but is rigidly protected against all twisting or warping action.

Referring to the operation of the unit, it will be seen in Fig. 5 that steam is supplied through the supply pipes S for distribution through the units 11. Air is drawn through the units by the blower unit 21, and the heated air is directed to its destination, not shown herein. As is unavoidable in such systems, boiler scales are entrained with the steam, and often the scales are of sufficient size to block or partially block the inlets of the tubes. In the present structure, the orifice ports 45 are not only difficult to block, because of their partially spherical contour, but

such ports and the surrounding structure serve as scale breakers, wherein, when a scale is lodged over one of the ports, it finds little support on the non-planar edges thereof, and therefore the scale will be subjected to a violent fluttering action resulting in its disintegration or dislodgment.

In addition, the ports 45 also serve as entrance nozzles for each of the tubes 37, having slightly restrictive characteristics, which is desirable to insure uniform steam distribution to all of the tubes.

It will be understood by those skilled in the art that the example of the invention as above described is intended to disclose certain inventive principles, which are obviously applicable to numerous other types of heat exchange devices. It is therefore intended that the invention shall be deemed commensurate with the scope of the following claims.

I claim:

1. In a heating device, a casing, a heating unit within said casing, said unit including spaced upper and lower headers and tubes connecting said headers, means connecting the upper header to the casing and including a rigid connection between the central portion of the upper header and the casing, said upper header having a projecting pinte on each extremity, brackets secured to opposite sides of the casing and having bearings formed therein for slidably receiving said pintles, whereby the ends of the upper header are permitted free expanding movement under axial guidance of said pinte and bearing connections, and cooperating means on the lower header and casing for permitting free guided movement of the lower header.

2. In a heating device, a casing, a heating unit within the casing, said unit including spaced upper and lower cylindrical headers and parallel tubes connecting the headers, said casing having offset recessed portions for partially receiving said headers, cylindrical pintles projecting from the ends of both headers, bearings on the casing for slidably and rotatably receiving the pintles of the upper header, said casing also having vertically slotted members for receiving the pintles of the lower header.

3. In a heat exchange device, a substantially rectilinear casing having top, bottom, and side walls connected together, a heating member mounted in said casing, said member comprising upper and lower headers and interconnecting expansible tubes, each of said headers being provided with end plates having a pinte projecting therefrom, opposed brackets secured to the casing adjacent the ends of the upper header but spaced therefrom, said brackets being formed with cylindrical bearings receiving the upper header pintles with longitudinal clearance, whereby the upper header may expand in an axial direction, and opposed slots formed in said casing adjacent the lower header, said slots receiving the lower header pintles for vertical and axial expansion of said header, said expansible tubes being bent whereby expansion of the heating member as a whole may be accommodated by extension of said tubes and movement of said lower header with respect to said slots.

EDMUND R. WALKER.
